UNITED STATES PATENT OFFICE.

JOHN C. COOKE, OF PHILADELPHIA, PENNSYLVANIA, ASSIGNOR TO NEW YORK SHIPBUILDING COMPANY, OF CAMDEN, NEW JERSEY, A CORPORATION OF NEW JERSEY.

BOILER.

SPECIFICATION forming part of Letters Patent No. 714,783, dated December 2, 1902.

Application filed October 4, 1901. Serial No. 77,517. (No model.)

To all whom it may concern:

Be it known that I, JOHN C. COOKE, a citizen of the United States of America, residing in the city and county of Philadelphia, in the State of Pennsylvania, have invented certain new and useful Improvements in Water-Tube Boilers, of which the following is a true and exact description, reference being had to the accompanying drawings, which form a part thereof.

10 My invention relates to water-tube boilers, having for its object to provide a simple and efficient construction for the circulation of the water and for the separation at a convenient point of sedimentary matter from the water.

15 The nature of my improvements will be best understood as described in connection with the drawings in which they are illustrated, and in which—

Figure 1 is a sectional side elevation of my 20 improved boiler; Fig. 2, a face view of one of the headers; Fig. 3, an enlarged sectional view taken in part through the headers and the ends of the duplex tubes connected therewith. Fig. 4 is a sectional view, on still a larger scale, 25 showing the connection of the tubes with the front header; Fig. 5, a sectional view on the line 5 5 of Fig. 4; Fig. 6, a sectional view on the line 6 6 of Fig. 4; Fig. 7, a sectional view illustrating a slight modification, and Fig. 8 30 a sectional view on the line 8 8 of Fig. 3.

A indicates the front header, having front and rear walls A' and A², and a longitudinal partition A³, dividing it into front and rear chambers a' and a².

35 B indicates the rear header. It will be understood that in usual construction the front and rear of the boiler is made up of groups of similar headers.

C and E are the outer and inner duplex 40 tubes, the tubes C connecting one of the chambers of the front header with the rear header. As shown, they are swaged at C' into the wall A² and have their ends projected into openings in the partition A³, as shown at C⁴, and 45 screwed onto annular nuts (indicated at D) to the inner threaded perforation, in which is screwed the internal tube E, opening into the

chamber a', while the outer tubes C open in the chamber a², being cut away, as indicated at C⁴, for this purpose. The rear ends of both 50 tubes C and E open into the rear headers B, and, as shown, the inner tube is held in central position by flanges E², extending out into contact with the rear end of the outer tubes. The chambers a' and a² of the front header 55 connect through nozzles F and F' with a steam and water drum G, situated above the header, the chamber a² connecting, as shown, through a passage formed by a partition G' in the drum and opening into the steam-space and behind 60 a baffle-plate G².

I indicates a mud-drum situated beneath the rear header B and connected therewith by nozzles H.

J is a bridge-wall between which and the 65 front wall K of the furnace are situated the grate-bars L, K' indicating the furnace-door.

M is a forwardly and upwardly extending baffle reaching from the top of the bridge J.

N is a partition separating the boiler-chamber 70 from the flue O and having a depending baffle-plate N', by means of which the products of combustion being first directed upwardly over the front end of the tubes are again directed downwardly over the center of 75 the tubes and upwardly into the flue O.

The circulation in my improved boiler is from the drum G downward through the nozzles F into the chamber a', thence backward through the inner tubes E to the rear header 80 B, and thence forward through the outer tubes C to the chamber a² of the front header, through which the water passes upward into the nozzles F' into the drum G, as shown, passing through the chamber formed by the partition G' into the steam-space of the boiler. It will be obvious that by my construction sedimentary matter is inevitably caught in the bottoms of the rear headers and the mud-receptacle appended thereto.

Having now described my invention, what I claim as new, and desire to secure by Letters Patent, is—

In a water-tube boiler the combination with

an upwardly and downwardly extending front header A divided by a longitudinal partition into two chambers a' and a^2 , of a single-chamber rear header B also extending upwardly and downwardly, duplex tubes C E connecting said headers, the outer and inner tubes connecting to different chambers of the front header and both opening into the rear header,

a steam and water drum connected to the tops of chambers a' and a^2 and a mud-receptacle 10 at the bottom of the rear header.

J. C. COOKE.
